(57) CLAIM

The ornamental design for a beverage machine, as shown and described.

DESCRIPTION

FIG. 1 is a perspective view of a beverage machine showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view thereof in a first use state;

FIG. 9 is a perspective view thereof in a second use state; and,

FIG. 10 is an exploded perspective view of FIG. 8 with the bottom separated for ease of illustration.

The broken lines in the drawings are included for the purpose of illustration and form no part of the claimed design.
